United States Patent Office

Des. 181,164
Patented Oct. 8, 1957

181,164

STAND FOR TELEVISION RECEIVERS

William Remstein, Syracuse, N. Y., assignor to
I. J. Elman, Syracuse, N. Y.

Application February 12, 1954, Serial No. 29,002

Term of patent 14 years

(Cl. D33—14)

FIG. 1.

FIG. 2.

Figure 1 is a perspective view of a stand for television receivers, showing the new design; and

Figure 2 is an enlarged fragmentary perspective view of one corner and leg shown in Figure 1.

I claim:

The ornamental design for a stand for television receivers, substantially as shown.
